Primary Examiner — Bao-Yen T Nguyen*Assistant Examiner* — Loryn K. LeBlanc(74) Attorney, Agent, or Firm — Che-Yang Chen; Law Office of Michael Chen(57) CLAIM

The ornamental design for a weighted blanket, as shown and described.

DESCRIPTION

FIG. 1 is a perspective view of the weighted blanket showing my new design;

FIG. 2 is a perspective view thereof from another angle;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a perspective view thereof when the weighted blanket is in use.

The broken lines shown in FIG. 9 are for the purpose showing the weighted blanket in an environment of use and form no part of the claimed design.

1 Claim, 9 Drawing Sheets(56)
